UNITED STATES PATENT OFFICE.

PETER SOLAINI, OF NEW YORK, N. Y.

EMBROIDERY DEVICE.

1,141,217.

Specification of Letters Patent.

Patented June 1, 1915.

Application filed July 7, 1914. Serial No. 849,417.

To all whom it may concern:

Be it known that I, PETER SOLAINI, a citizen of Italy, and residing at New York, in the county of New York and State of New York, have invented new and useful Improvements in Embroidery Devices, of which the following is a specification.

The object of my invention is the production of a simple, practical and inexpensive device for embroidering or working raised designs in thread upon a fabric.

The invention consists in general of a holder within which there is mounted a reciprocating needle carrier and a special feature of the invention resides in the provision of a tensioning device which operates as the needle is withdrawn from the fabric to draw on one side of the loop of thread which the needle has just previously carried through the fabric. This renders the loop-forming action of the needle uniform and even. For the purpose of varying the size or formation of the loops thus produced by the needle, the invention contemplates the provision of means for varying the stroke of the needle carrier and hence of the needle. After working in a desired design or figure upon the fabric the loops are usually clipped so as to leave the design appearing raised or upstanding upon the face of the fabric.

The tensioning device is usually in the form of a thread-engaging element slidably mounted on the needle carrier and arranged to clamp the thread or yarn against a shoulder on the carrier. The needle carrier is reciprocated by a suitable handle and this handle is preferably connected with the slideable tensioning element so as to operate it in time with the movement of the needle.

A special feature consists in adjusting the connection between the operating handle and tensioning element to vary the tension exerted upon the thread.

A further special feature of the invention consists in mounting the needle in the needle carrier so that it can yield laterally to a certain extent. The effect of this is to cause the needle to step forward each time it is withdrawn from the fabric and so produce an automatic and natural feeding action of the device over the fabric. This yieldable characteristic also prevents the needle from being broken by accidental sidewise pushing on the device.

Other novel features of the invention will appear as the specification proceeds.

The accompanying drawings illustrate in concrete form a practical embodiment of the invention but it will be understood that various changes and modifications may be made without departing from the true scope and spirit of the invention.

Figure 1, is a perspective view of an embodiment of the invention. Fig. 2, is a drop perspective view showing the several parts of the device. Fig. 3, is a vertical sectional view of the device as in use, showing the needle just withdrawn from the fabric and stepped forward ready to make the next down stroke. Fig. 4, is a broken view showing the lower portion of the device, with the needle just completing its downward stroke. Fig. 5, is a similar view with the needle just about completing its upward stroke. Fig. 6, is a perspective view showing a flower design partially worked upon a fabric and illustrating the appearance of the pile-forming loops both before and after being trimmed or clipped.

The body or holder portion of the device is shown in the form of a tubular member 7 having a foot 8 to bear upon the fabric. The needle carrier is shown as a hollow cylindrical member 9 slidably engaged in the holder so as to reciprocate therein.

10 designates the needle mounted in the lower end of the needle carrier. This may be an ordinary sewing machine needle.

The needle carrier is usually guided and held against turning in the holder by providing it with a lug 11 working in a guide slot 12 in the holder. The lug 11 may be perforated as shown, to form a thread guide. The upward stroke of the needle carrier is limited, in the illustration by an outstanding lug 14 on the lower end of the tubular holder (see Fig. 3.) The down-stroke of the carrier and hence the active stroke of the needle is governed in the case shown by an annular abutment 15 adjustably engaged on the screw-threaded shank portion 16 of the carrier and designed to engage the top of the holder. This annular abutment is internally threaded to fit the screw threads of the carrier and it is usually secured in its adjusted position by a lock nut 17.

The needle carrier is reciprocated by a suitable handle 20 and this handle is, in the present case, utilized also to operate the ten-

sion device. This is accomplished by connecting the handle direct with the movable element of the tension device.

In the form of tension device illustrated in the present disclosure there is a movable thread-supporting element 21, slidably mounted inside the tubular body of the needle carrier and this member is hooked at its lower end to provide spaced substantially parallel side portions 22 forming between them a thread pocket to carry the thread in clamped engagement with a relatively fixed abutment. This abutment is shown in the form of a looped member 23 through which the clamp member is passed so as to be guided thereby. The handle 20 is mounted direct upon the upper end of the movable clamp member, it being, as indicated in Fig. 3, adjustably secured thereon by means of a nut 24, engaged on the threaded end portion 25 of said member.

The reciprocating tension clamp is guided at its upper end by working through a guide opening 27 formed in the cap 28 which is secured on the upper end of the needle carrier. The down stroke of the clamp member is determined by the handle coming into engagement with the top of the cap. This will be clear from Fig. 3. The up stroke of the clamp is limited by the thread pocket on the lower end thereof engaging with the relatively fixed abutment loop, as also appears in Fig. 3.

The thread or yarn, indicated at 30 is guided across the thread pocket by being passed through guide openings 31, in the parallel sides 22 of the clamp member. The section of thread lying in the pocket is thus always in position to be clamped against the relatively stationary guide loop.

The needle carrier is preferably held against too free sliding movement in the holder by frictional retarding means such as the bowed spring 33 on the carrier bearing against the inner wall of the holder.

In the construction illustrated, the needle is allowed to a certain lateral yielding action by fastening it in a chuck in the form of a socketed block 35 which is pivoted at 36 in the lower end of the needle carrier. The needle is removably and adjustably held in the socket of the chuck by a clamp screw 37. The needle chuck is held normally with the needle in a forwardly tilted position (Figs. 1 and 3) by a spring 38 bearing upon the upper forward corner of the chuck, as shown in Fig. 3.

In operation, the holder portion of the device is held in one hand with the foot of the device pressed firmly upon the stretched cloth or fabric 40. With the other hand the handle 20 is grasped and a reciprocating movement is imparted to the needle carrier. Upon the downstroke of the needle carrier the needle carries a long loop 41 of thread

down through the fabric (Fig. 4). During this downstroke the thread-tensioning device releases its grip on the thread (Fig. 4) and the thread is therefore free to slide through the needle to furnish all the thread needed for the full loop. On the up stroke of the needle carrier, the upward pull on the handle first lifts the movable clamp element into thread-gripping position and as the hooked lower end of the clamp engages with the guide loop 23, a positive connection is afforded between the handle and needle carrier and the needle carrier then moves with the handle. During this upward retractive movement of the needle therefore, the thread forming one side of the loop just produced by the needle is gripped in the tension device (Fig. 5) and so the one side of the thread loop is thus drawn back through the fabric. The completion of this upward movement leaves a relatively short loop 42 remaining on the underside of the fabric (Fig. 3). The forward slant of the needle causes it to act as an inclined plane so that as it penetrates the fabric on its downstroke (Figs. 1 and 2) it serves to draw the device bodily forward a distance approximately equal to its inclination. Upon the upstroke, the pivotal mounting permits the needle to straighten out (Fig. 5) and then as the tip of the needle clears the fabric the spring throws the needle forward to its original inclined position so that it in effect automatically steps out and therefore on its next stroke enters the fabric at a point in advance of the last formed loop (Fig. 3).

The size of the loops formed on the underside of the fabric can be varied by changing the stroke of the needle carrier through the medium of the adjustable abutment 15. A further variation is obtainable by varying the stroke of the tension device through the medium of the adjusting nut 24.

Fig. 6 shows a piece of fabric whereon there is marked a flower design 50 one of 110 the petals 51 of which has been worked in with the loops forming an upstanding pile fabric and two other petals 52 which have been trimmed so as to present the appearance of a flower resting upon the surface of 115 the fabric.

In addition to providing for formation of different-sized loops the adjustments of the needle carrier and tension device provide different degrees of tension on the thread 120 and allow for the use of different kinds and grades of thread or yarn. The automatic feeding action renders it necessary only to work the needle carrier up and down and to guide the device in the direction desired. 125

What I claim is:—

1. In an embroidery device, a tubular holder, a tubular needle carrier slidably engaged in said holder provided with a threaded shank portion projecting above the 130

top of the holder, a needle mounted in the lower end of the carrier, a threaded abutment engaged on the upper threaded shank portion of the needle carrier and arranged 5 by engagement with the top of the holder to limit the downstroke of the needle carrier, an outwardly projecting looped member on the lower end of the needle carrier, a rod loosely engaged in the carrier extending up 10 through said looped member and up through the tubular carrier, a closure to the upper end of said tubular carrier provided with a guide opening through which the upper end of the rod projects, a handle on the upper 15 extended end of the rod, a thread pocket on the lower end of the rod arranged to cooperate with the looped member aforesaid and a spring on the needle carrier bearing against the inner wall of the tubular holder to hold said carrier against too free movement in the holder. 20

2. In an embroidery device, the combination with a holder, a needle carrier reciprocating therein, a needle mounted on said carrier, a reciprocating thread-tensioning element reciprocably mounted on the carrier and means for varying the stroke of said reciprocating thread-tensioning element on the needle carrier. 25
